UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR A SCROLL-CLAMP.

46,739.

Specification for Design.

Patented Dec. 8, 1914.

Application filed September 14, 1914. Serial No. 861,724. Term of patent 3½ years.

To all whom it may concern:

Be it known that I, CHARLES E. JONES, a citizen of the United States, residing at Chicago, in the county of Cook and State of Illinois, have invented a new, original, and ornamental Design for a Scroll-Clamp, of which the following is a specification, reference being had to the accompanying drawing, forming part thereof.

Figure 1, is a side elevation of a scroll

clamp, showing my new design. Fig. 2, is a front elevation of the same.

I claim:

The ornamental design for a scroll clamp, as shown.

CHARLES E. JONES.

Witnesses:

C. M. BAUMEISTER,

V. C. LINDSTROM.
